(57) **CLAIM**

The ornamental design for a portion of a display screen with avatar, as shown and described.

DESCRIPTION

FIG. 1 is a view of a first embodiment of our design; FIG. 2 is a view of a second embodiment of our design; FIG. 3 is a view of a third embodiment of our design; FIG. 4 is a view of a fourth embodiment of our design; FIG. 5 is a view of a fifth embodiment of our design; and, FIG. 6 is a view of a sixth embodiment of our design. The outer perimeter shown in dashed broken lines in FIGS. 1-6 illustrates a portion of a display screen that forms no part of the claimed design.
